(57) **CLAIM**

The ornamental design for a condiment shaker, as shown and described.

DESCRIPTION

FIG. 1 is a perspective view showing my new design.

FIG. 2 is a front end view thereof.

FIG. 3 is a rear end view thereof.

FIG. 4 is a left view thereof.

FIG. 5 is a right view thereof.

FIG. 6 is a top view thereof.

FIG. 7 is a bottom view thereof.

FIG. 8 is an exploded perspective view of my new design, illustrating the condiment shaker adapted for placing on condiment shaker tray, wherein the broken lines of the condiment shaker tray shown in FIG. 8 form no part of the claimed design; and,

FIG. 9 is a perspective view of my new design, illustrating a plurality of condiment shaker on condiment shaker tray, wherein the broken lines of the condiment shaker tray shown in FIG. 9 form no part of the claimed design.
